United States Patent Office

Des. 175,948
Patented Nov. 1, 1955

175,948

PHONOGRAPH TONE ARM

Bruce Kamp, Springfield, Pa., assignor to The Astatic Corporation, Conneaut, Ohio, a corporation of Ohio

Application May 13, 1955, Serial No. 35,966

Term of patent 7 years

(Cl. D26—14)

Figures 1, 2 and 3 are perspective views of a phonograph tone arm showing my new design; and

Figure 4 is a front view taken from the left end of Figure 1.

I claim:

The ornamental design for a phonograph tone arm, as shown.
